UNITED STATES PATENT OFFICE.

DAVID KISCH, OF NEW YORK, N. Y.

DESIGN FOR A RUCHE-HOLDER.

Specification forming part of Design No. 6,880, dated September 9, 1873; application filed August 4, 1873.
[Term of Patent 3½ years.]

To all whom it may concern:

Be it known that I, DAVID KISCH, of the city, county, and State of New York, have invented a new and useful Design for a Ruffling-Drum, of which the following is a specification:

The drawing represents a perspective view of my new design for ruffling-drum.

This invention relates to a new form or configuration of the stand or support of a drum used for holding ruffling or other fancy fabric, and also to a new design of the ornamentation of such stand or support.

The stand consists of two uprights, A A, which carry or support the shaft of the drum B that is held between them, said drum being of suitable shape and size, and arranged to support ruffling or other fancy fabric wound thereon. Each upright A of the stand is made of the form shown in the drawing—that is to say, it has a V-shaped notch cut into its lower

end in the middle, and has each of its sides composed at the lower part of a vertical straight line, and thence upward in the form of an ogee, the ogee connecting the straight horizontal top line. The face of each upright is ornamented or decorated by the representation of a female leaning on a steering-wheel, and is further ornamented by arabesques or ornamental scrolls, as shown. The ends of the drum B where exposed to view may also be ornamented by suitable ornamental scrolls.

What I claim as my invention is—

1. The design for a ruche-holder herein described, with or without the ornamentation on the upright A, substantially as set forth.
2. The design for the ornamentation of the upright A, as shown.

DAVID KISCH.
